US0D1099827S

(12) **United States Design Patent** (10) **Patent No.:** **US D1,099,827 S**
(45) **Date of Patent:** **** Oct. 28, 2025**

(54) **CABLE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **M. Evans Hankey**, San Francisco, CA (US); **Anne-Marie Heck**, San Francisco, CA (US); **Moises Hernandez Hernandez**, Palo Alto, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Kainoa Kwon-Perez**, San Francisco, CA (US); **Nicolas Pedro Lylyk**, Los Gatos, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/877,256**

(22) Filed: **Jun. 5, 2023**

(51) **LOC (15) Cl.** **13-03**

(57) **CLAIM**

The ornamental design for a cable as shown and described.

DESCRIPTION

The patent or application file contains at least one drawing executed in color. Copies of this patent or patent application

(Continued)

publication with color drawing(s) will be provided by the Office upon request and payment of the necessary fee. FIG. 1 is a right side view of a cable showing the claimed design;

FIG. 2 is a right side perspective view thereof; FIG. 3 is a front right side perspective view thereof; FIG. 4 is a front view thereof; FIG. 5 is a front left side perspective view thereof; FIG. 6 is another front left side perspective view thereof; FIG. 7 is a left side perspective view thereof; and, FIG. 8 is a left side view thereof.

The cable is shown with a wavy break line at its end to indicate that portions of the cable beyond the break line and the length of the cable form no part of the claimed design.
